UNITED STATES PATENT OFFICE.

JACOB KRAUSS, OF LEXINGTON, KENTUCKY.

VEHICLE.

SPECIFICATION forming part of Letters Patent No. 703,601, dated July 1, 1902.

Application filed November 6, 1900. Serial No. 35,597. (No model.)

To all whom it may concern:

Be it known that I, JACOB KRAUSS, a resident of Lexington, in the county of Fayette and State of Kentucky, have invented certain new and useful Improvements in Vehicles; and I do hereby declare the following to be a full, clear, and exact description of the invention, such as will enable others skilled in the art to which it appertains to make and use the same.

My invention relates to an improvement in vehicles, and more particularly to a vehicle-body, the object of the invention being to provide a vehicle-body which will greatly economize space, be easily accessible to passengers, and which will be extremely ornamental in appearance.

With this object in view the invention consists in certain novel features of construction and combinations and arrangements of parts, as will be more fully hereinafter described, and pointed out in the claim.

In the accompanying drawings, Figure 1 is a view illustrating my improvements. Fig. 2 is a view showing the door open, the front seat pushed forward, and tail-gate down; and Figs. 3, 4, and 5 are views of details of construction.

My improved vehicle-body comprises the base or bottom 1, sides 2, of any desired ornamentation, uprights 3, and top or cover 4, supported thereon. A door 5 is hinged on each side of the body between uprights 3 and made with suitable latches 6 to hold them in their closed position.

The front seat 7 is supported on pivoted links 8^a, which when the seat is in its normal position locates the same in the position shown in Fig. 1 or, in other words, in the door-space or passage-way to the rear seat, but which can be readily pushed forward on the links and be entirely out of the door-space or passage-way and permit free ingress to or egress from the vehicle.

The rear seat 8 comprises the seat portion 9, having a flap or curtain 10 at its forward edge, and back 11 at the rear edge of the seat portion and disposed at right angles thereto and connected with the seat portion by metal brackets or arms 12, which support the lower edge of the back slightly above the plane of the seat portion, for a purpose which will

hereinafter appear. The seat portion 9 is cushioned and supported on diametrically opposite flanges or rails 13 on the sides 2 and 55 is held against accidental displacement by means of a clamp 14^a. The clamp 14^a comprises a metal bar secured at one end to the bottom of the seat and then bent downward and outward and terminates in an upwardly-projecting tooth 14^b to fit behind flange 13, and a threaded rod 14^c is secured to the seat and extends through a hole in the clamp and is provided with a thumb-nut 14 to force the clamp against flange 13 and secure the seat 65 against movement.

The tail-gate 15 of the body is hinged at its lower edge and supported when open by straps 16, and when in its closed position will rest directly beneath and flush with the 70 lower edge of the back 11, which latter can be made of a solid board and cushioned and ornamented on its rear face to correspond with the ornamentation of the tail-gate, so as to give the appearance of a single solid panel. 75 This construction not only gives to the vehicle an ornamental and attractive appearance, but also adds greatly to the strength of the seat-back, as the latter is held firmly and rigidly on top of the tail-gate, and a great 80 portion of the strain on the brackets 12 is removed.

It will be seen that when desired the rear seat can be entirely removed by simply loosening thumb-screws 14, and hence give room in 85 the vehicle for trunks and large packages, and when the rear seat is in place every inch of the vehicle-body is utilized, leaving no waste space, but at the same time leaving ample space for comfort of the passengers. 90

Various slight changes might be made in the general form and arrangement of the several parts described without departing from the spirit and scope of my invention, and hence I would have it understood that 95 I do not wish to limit myself to the precise details set forth, but consider myself at liberty to make such slight changes and alterations as fairly fall within the spirit and scope of my invention.

Having fully described my invention, what I claim as new, and desire to secure by Letters Patent, is—

In a vehicle, the combination with a body

having guides in the sides of its rear portion, a door and a jump-seat mounted on pivoted supports and normally projecting partially across the door-space, of a rear seat mounted 5 to slide on the guides in the body, clamps secured to the bottom of the rear seat and engaging said guides, a back for the rear seat and having an exposed lower edge, rigid brackets securing said back to the rear seat, 10 and a prop hinged at its lower edge to the rear end of the body and engaging at its upper

edge, the exposed lower edge of the back of the rear seat, said back and prop being in the same vertical plane.

In testimony whereof I have signed this 15 specification in the presence of two subscribing witnesses.

JACOB KRAUSS.
